UNITED STATES PATENT OFFICE.

VERGIL MULHOLLAND, OF EDGEWOOD, PENNSYLVANIA, ASSIGNOR TO HEYL & PATERSON, INC., OF PITTSBURGH, PENNSYLVANIA, A CORPORATION OF PENNSYLVANIA.

APPARATUS FOR HANDLING GLASSWARE.

1,016,428.

Specification of Letters Patent.

Patented Feb. 6, 1912.

Application filed June 24, 1908. Serial No. 440,202.

To all whom it may concern:

Be it known that I, VERGIL MULHOLLAND, a resident of Edgewood, in the county of Allegheny and State of Pennsylvania, have 5 invented a new and useful Improvement in Apparatus for Handling Glassware; and I do hereby declare the following to be a full, clear, and exact description thereof.

My invention relates to apparatus for 10 handling glassware.

The object of my invention is to provide apparatus for mechanically lifting the ware from open molds or other receptacles containing the ware and depositing the same 15 upon a conveyer by means of which the ware is transferred to the leer, thereby doing away with the great amount of labor and expense heretofore incurred in doing this work by manual labor.

20 To these ends my invention comprises the novel features hereinafter set forth and claimed.

In the drawings Figure 1 is an end elevation partly in section of my improved apparatus; Fig. 2 is a plan view thereof partly in section; Fig. 3 is a side view of the glass machine and transfer mechanism; Fig. 4 is an enlarged view of the mechanism for transferring the ware to the leer carrier; 30 Fig. 5 is an enlarged plan view detail partly broken away of the last named apparatus; Fig. 6 is a like view showing a portion of the transfer apparatus from the mold; and Figs. 7, 8 and 9 are enlarged details.

35 I have illustrated my invention in connection with a common form of machine for making glassware, in which the numeral 2 designates the base or platform mounted on the trucks 3. Mounted on the base 2 is 40 the central standard or column 4 which carries the revolving table 5, said table carrying the molds 6 which are arranged at intervals thereon.

I have not deemed it necessary to illustrate the mechanism for pressing and blowing the ware, nor the mechanism by means of which the rotary movement is imparted to the table, or other details, as these form no part of my present invention.

50 I do not wish to limit my invention to the lifting of ware from molds as in the illustrations, but wish to include within the scope of my invention the lifting of the ware from any receptacle into which the

ware may have been introduced after leaving the mold. 55

A shaft 7 is journaled in suitable bearings 7^a in the frame 8 and on said shaft is the pulley 9 which is connected up by the belt 9^a to a suitable motor. On the shaft 7 is the 60 worm 10 which meshes with the worm wheel 11 on the shaft 12. A gear wheel 11^a on the shaft 6 meshes with the gear wheel 13 on the shaft 14, and a bevel pinion 15 on said shaft meshes with the bevel pinion 65 16 on the shaft 17. A bevel pinion 18 on the shaft 17 meshes with the bevel pinion 19 on the shaft 20. Mounted on the shaft 20 is the cam wheel 21, which has formed on its periphery the cam 22. A second cam 70 wheel 23 on the shaft 20 is also provided with the cam 24. A lever 25 is pivoted at 26 to the frame 2 and said lever is provided with the idle rollers 28 between which the cam 22 is adapted to move. A link 29 is 75 connected to the lever 25, said link being connected to the short arm 30 which has the collar 31, keyed to the vertical shaft 32.

A lever 33 is pivoted at 34, said lever having the idle rollers 34 between which the 80 cam 24 moves. A link 35 is connected to the lever 33 and said link is connected to the arm 36, keyed to the sleeve 37 on the shaft 32. Keyed to the sleeve 37 is the short arm 38. A link 39 is connected to the short arm 85 38 and said link is connected to the arm 40, fulcrumed at 41 to the frame 42. The frame 42 is loosely mounted on the sleeve 37 to rotate thereon, but keyed to the shaft 32 by means of the feather 43. At the end of the 90 arm 40 is the clevis 44 which has the pins 45 engaging the bifurcated end 46 of the arm 40. Extending through the clevis 44 is the rod 47, and pivoted to the inner end of said rod by the pin 49 extending through the 95 frame 42. A spring 50 is interposed between the head of the rod 47 and the clevis 43, said spring acting normally to close the scissor arms 48. Links 51 are connected to the scissor arms and to the clevis 43. 100

On the shaft 20 is the cam 52 which is adapted to engage the idle roller 53 on the arm 54, said arm being pivoted to the frame at 55. Connected to the outer end of the arm 54 is the link 56 connected at its upper end to the collar 57 loosely mounted on the hub of the frame 42.

Adjacent to the apparatus just described

is the stand 58. Journalized in said stand is the vertical shaft 59 and mounted on said shaft is the cam 60. This cam 60 is adapted to engage with the idle roller 61 on the arm 62. This arm 62 is fulcrumed at 63 on the frame 64. The outer end of the arm 62 carries the solenoid 65 which enters the recess formed for it in the frame 64.

The frame 64 has the hub portion 66 through which the pin 67 passes and upon which said frame is adapted to swing. The frame 64 has the upwardly extending arm 68 and carried by said arm is the ring 69. A finger 70 is pivoted at 71 to the arm 68, as clearly shown in Fig. 5. A spring 70^a is secured at one end to the arm 68 and at the other end bears against the finger 70.

The frame 72 of the leer conveying apparatus has the permanent shelf 73 and the tilting shelf 74. The tilting shelf 74 is pivoted at 75 and the inner end of said shelf is weighted as at 76. This weight acts normally to throw the shelf up into the position shown in dotted lines in Fig. 4. Below the tilting shelf 74 is the angle 77 which is insulated from said shelf by insulating material 78. This angle 77 has the electrical contacts 79 and 80. A U shaped bar 81 is secured to the frame and has the binding screw 82. Wires 83 and 84 are connected up to the terminals 80 and 82 and said wires lead to the solenoid 65. The U shaped piece 81 is insulated from the terminal 82 by means of the insulating material 85.

35 A spring 86 is secured to the hub 58^a on the frame 58, said spring engaging with the lug 87 and adapted to return the frame 64 to its normal position. An adjustable stop 88 is screwed into the lug 89 on the frame 64 and said screw is adapted to bear against the end of the shelf 90 which forms part of the frame 58, said shelf forming a support for the roller 61 when the frame 64 swings around to the position indicated in dotted lines Fig. 5.

At the upper end of the shaft 59 is the sprocket wheel 92 which is driven by the chain 93. This chain 93 is provided at intervals with the flights 94, with curved arms 95, said arms acting in the manner hereinafter set forth to convey the ware to the leer along the frame 72. Such a form of conveyer is illustrated in Letters Patent of the United States No. 842,209, granted to me and C. R. Knapp, on the 29th day of January, 1907.

When my improved apparatus is in use, when the rotary table 5 carrying the molds brings one of the molds around containing the finished article such as a fruit jar, the mold is opened and the scissor arms 48, as indicated in Fig. 2, will engage the neck of the jar. These scissor arms are forced apart by the action of the arm 40, brought into such position by the action of the cam 24, through

the intermediate arms and links described so as to be forced open to engage the jar in the manner shown. After the jar has been seized in this manner by the arms 48 the cam 22 of the cam wheel 21 comes around 70 in such position as to move the arm 25 and through the connections described the frame 42 is swung around in such position as to bring the jar in position over the shelves 73 and 74, as shown in Fig. 6. Just prior, 75 however, to the swinging of the frame 42 into this position the arm 54 is slightly raised by the cam 52 so as to lift the link 56 and the frame 42, whereby the jar is lifted slightly from the mold in order to 80 clear the base of the mold when the frame 43 swings outwardly. When the frame 42 has been swung over in such position as to bring the jar over the shelves 73 and 74, the cam 52 acts to lower the arm 54 and 85 with it the frame 42, whereby the jar is lowered into position to rest upon the shelves 73 and 74 within the ring 69. When the jar has been deposited upon the shelves in this manner the cam 23 acts through the connections described to open the scissor arms 48 and release the jar, while at the same time the cam 22 acts to return the frame 42 to the position indicated in Fig. 2, in position 90 to grasp the next jar as it comes around on 95 the revolving table 5. As soon as the jar has been deposited upon the shelves 73 and 74 the weight of said jar will act to lower the tilting shelf 74 to the position indicated in Fig. 4 and the lowering of said shelf will 100 make the electric contact between the terminals 79 and the terminal 82, whereby the solenoid 65 is energized and the arm 62 lowered, which throws the roller 61 up into position to be engaged 105 by the cam 60. The enlargement of the rotating cam 60 coming into engagement with the roller 61 acts to swing the frame 64 into the position indicated in dotted lines Fig. 5, whereupon the jar is moved along 110 the shelves 73 and 74 and the movement of the chain 93 is so timed that one of the curved arms 95 will travel around in position to move the jar from the shelves and when the stop 96 is reached the finger 70 115 will act to open the ring 69 and release said jar and permit it to be received by the flight 94 which will move the jar along the frame 72 to the leer. As soon as the jar has been freed from the frame 64 the enlarged portion of the cam 60 will have traveled over the roller 65 and said frame 64 will then be free to assume its normal position to which it will be brought by means of the spring 86. Furthermore, just as soon as the 125 jar leaves the tilting shelf 74 said shelf will be raised by the weight 76 and the electrical contact broken so that the roller 61 will be lowered out of the path of the cam 60 until the next operation. The frame 64 130

having been returned to its normal position another jar is deposited upon the shelves by the swinging frame 42 and the operation just described is repeated.

5. It is apparent that the apparatus may be arranged to operate in connection with a number of different molding machines arranged in proximity to the conveyer. In that case the transfer device for each machine would be timed to operate with the others in such a manner as to fill the flights in succession.

By my invention the jars contained in the molds, or other receptacles, are transferred quickly to the conveyer and carrier forward to the leer without any handling, and as a consequence the liability of breakage is reduced, while at the same time the manual labor heretofore employed for carrying the ware from the molds to the leer carrier is dispensed with and the whole operation carried on mechanically.

What I claim is:

1. In apparatus for handling glassware, 25 the combination of a mold or other receptacle, a conveyer adjacent to same, a ware support in close proximity to said conveyer, means for transferring the ware from said mold to said support, said support being 30 separate from said transferring means, and means operated by the movement of the conveyer for transferring the ware from said support to said conveyer.

2. In apparatus for handling glassware, 35 the combination of a mold or other receptacle, a conveyer adjacent to same, a ware support in close proximity to said conveyer, means for transferring the ware from said mold to said support, and a swinging frame 40 in position with reference to said support to move the ware from said support onto said conveyer.

3. In apparatus for handling glassware, 45 the combination of a mold or other receptacle, a conveyer adjacent to same, a ware support in close proximity to said conveyer, means for transferring the ware from said mold to said support, a swinging frame extending over said support, and a cam adapted 50 to engage said frame.

4. In apparatus for handling glassware, the combination of a mold or other receptacle, a conveyer adjacent to same, a ware support in close proximity to said conveyer, 55 means for transferring the ware from said mold to said support, a swinging frame extending over said support, and a rotary cam adapted to engage said frame.

5. In apparatus for handling glassware, 60 the combination of a mold or other receptacle, a conveyer adjacent to same, a ware support in close proximity to said conveyer, means for transferring the ware from said mold to said support, a spring actuated 65 swinging frame extending over said sup-

port, and a rotary cam adapted to engage said frame.

6. In apparatus for handling glassware, the combination of a mold or other receptacle, a conveyer adjacent to same, a ware support 70 in close proximity to said conveyer, means for transferring the ware from said mold to said support, a swinging frame extending over said support, a projection on said frame, a rotary cam adapted to engage 75 said projection, and gravity means for withdrawing said projection from the path of said cam.

7. In apparatus for handling glassware, 80 the combination of a mold or other receptacle, a conveyer adjacent to same, a ware support in close proximity to said conveyer, means for transferring the ware from said mold to said support, a swinging frame extending over said support, a projection on 85 said frame, a rotary cam adapted to engage said projection, a rock-arm on said frame, a projection on said arm, and means for operating said arm to bring said projection into the path of said cam.

8. In apparatus for handling glassware, 90 the combination of a mold or other receptacle, a conveyer adjacent to same, a tilting ware-support in close proximity to said conveyer, means for transferring the ware from 95 said mold to said support, mechanism for transferring the ware from said support to said conveyer, and means for operating said mechanism by the contact of said ware with said support.

9. In apparatus for handling glassware, 100 the combination of a mold or other receptacle, a conveyer adjacent to same, a tilting ware-support in close proximity to said conveyer, means for transferring the ware from 105 said mold to said support, mechanism for transferring the ware from said support to said conveyer, electrically operated mechanism for operating said transferring mechanism, and means for closing the circuit by 110 the weight of said ware on said support.

10. In apparatus for handling glassware, the combination of a mold or other receptacle, a conveyer adjacent to same, a tilting ware-support in close proximity to said conveyer, means for transferring said ware from 115 said mold to said support, a swinging frame extending over said support, a movable arm on said frame, a projection on said arm, a rotary cam, a solenoid in said arm, means for making and breaking connections to said solenoid by the tilting of said support, whereby said arm is moved to bring said projection into the path of said cam.

11. In apparatus for handling glassware, 120 the combination of a mold or other receptacle, a conveyer adjacent to same, a support in close proximity to said conveyer, means for transferring said ware from said mold to said support, a swinging frame extending 125

130

- over said support, a holder for said ware on said frame, mechanism for swinging said frame to transfer said ware to said conveyer, and means for opening said holder.
- 5 12. In apparatus for handling glassware, the combination of a mold or other receptacle, a conveyer adjacent to same, a support in close proximity to said conveyer, means for transferring said ware from said mold
- 10 to said support, a swinging frame extending over said support, a holder for said ware on said frame, a hinged section on said holder, a stop in the path of said hinged section, and means for moving said frame.
- 15 13. In apparatus for handling glassware, the combination of a mold or other recepta-

cle, a conveyer adjacent to same, a support in close proximity to said conveyer, means for transferring said ware from said mold to said support, a swinging frame extending 20 over said support, a holder for said ware on said frame, a hinged section on said holder, a spring actuated finger on said section, a stop in the path of said hinged section, and means for moving said frame. 25

In testimony whereof, I the said VERGIL MULHOLLAND have hereunto set my hand.

VERGIL MULHOLLAND.

Witnesses:
